CLAIM

The ornamental design for a video analytics device, as shown and described.

DESCRIPTION

FIG. 1 is a perspective view of a video analytics device showing our new design.

FIG. 2 is a front elevational view thereof.

FIG. 3 is a back elevational view.

FIG. 4 is a top plan view.

FIG. 5 is a bottom plan view.

FIG. 6 is a left side elevational view; and,

FIG. 7 is a right side elevational view.

The broken lines depict portions of the video analytics device in which the design is embodied that form no part of the claimed design.
